US00D974354S

(12) **United States Design Patent** (10) Patent No.: **US D974,354 S**
(45) Date of Patent: ** Jan. 3, 2023

(54) **ELECTRONIC DEVICE**(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, San Francisco, CA (US); **Clement Tissandier**, San Francisco, CA (US); **Eugene Antony Whang**, San Francisco, CA (US)

(73) Assignee: **Apple Inc.**, Cupertino, CA (US)(**) Term: **15 Years**(21) Appl. No.: **29/728,327**(22) Filed: **Mar. 17, 2020**(51) LOC (14) Cl. ..... **14-02**(52) U.S. Cl. **D14/341**
USPC ..... **D14/125-129, 138 AA, 138 AB, 138 AC, 14/138 AD, 138 C, 138 G, 155-159, 14/160-173, 187-188, 189-198, 14/203.1-203.8, 204-216, 217-222, 14/239, 248, 257-258, 315-318, 14/341-347, 371, 374, 413, 432, 433, 14/439-441, 496, 498-506; D6/308, D6/310; D10/50, 65, 104.1; D18/6-7; D21/324, 329-330, 332**(58) **Field of Classification Search**

USPC ... D14/125-129, 138 AA, 138 AB, 138 AC, 14/138 AD, 138 C, 138 G, 155-159, 14/160-173, 187-188, 189-198, 14/203.1-203.8, 204-216, 217-222, 14/239, 248, 257-258, 315-318, 14/341-347, 371, 374, 413, 432, 433, 14/439-441, 496, 498-506; D6/308, D6/310; D10/50, 65, 104.1; D18/6-7; D21/324, 329-330, 332
CPC ... H04M 1/0202; H04M 1/0266; H04M 1/725

CLAIM

The ornamental design for an electronic device, as shown.

DESCRIPTION

FIG. 1 is a front perspective view of an electronic device showing the claimed design;

FIG. 2 is a rear perspective view thereof;

FIG. 3 is another rear perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

1 Claim, 7 Drawing Sheets

FIG. 1

FIG. 2

FIG. 3

FIG. 4

FIG. 5

FIG. 6

FIG. 7

FIG. 8

FIG. 9
